CLAIM

The ornamental design for a display screen or portion thereof with graphical user interface, as shown and described.

DESCRIPTION

The FIGURE is a front view of a display screen or portion thereof with graphical user interface showing our design. The outer-most broken line showing the display screen is included for the purpose of illustrating environmental structure and forms no part of the claimed design. The remaining broken lines, which make up portions of the graphical user interface, form no part of the claimed design.
